(57) **CLAIM**

The ornamental design for a hummingbird feeder, as shown and described.

DESCRIPTION

FIG. 1 is a Top plan view of the hummingbird feeder showing my new design;

FIG. 2 is a front elevation view thereof;

FIG. 3 is a bottom plan view thereof; and,

FIG. 4 is a perspective view thereof.

The back, right and left views are similar in appearance to the front.

The broken lines shown in FIG. 1 are for illustrative purposes only and form no part of the claimed design.
